UNITED STATES PATENT OFFICE.

PETER J. PECK, OF CHICAGO, ILLINOIS.

RAILROAD-TIE.

1,087,819.

Specification of Letters Patent.

Patented Feb. 17, 1914.

Application filed November 7, 1913. Serial No. 739,777.

To all whom it may concern:

Be it known that I, PETER J. PECK, a citizen of the United States, residing at Chicago, in the county of Cook, and State of Illinois, have invented certain new and useful Improvements in Railroad-Ties; and I do hereby declare the following to be a full, clear, and exact description of the invention, such as will enable others skilled in the art to which it appertains to make and use the same.

This invention relates to new and useful improvements in railroad ties and has for its object the provision of a metallic tie which will combine the advantages of a metallic tie and those of a wooden tie in the same device.

Another object of the invention is the provision of a tie having a rail holding member formed integral therewith which will also serve as a rail bearing.

A further object of the invention is the provision of a tie which may be used on both a straightaway and a curved track, without in any way changing the construction of the same.

With the above and other objects in view I will now proceed to describe the invention in the following specification and accompanying drawings, in which,

Figure 1 is a view of my improved tie showing it partly in section to illustrate the construction thereof, and Fig. 2 is a view in elevation of my improved tie as it would appear when in use on curves.

Referring to the drawings by characters of reference 1 indicates generally my improved railroad tie, which is preferably composed of the rectangular metallic casing 2. This metallic casing is provided intermediate its ends with the apertures 3, which are so stamped as to form the tongues 4. These tongues 4 are adapted to be bent inwardly as clearly illustrated and form the inner abutment for the ends of the wooden block 5, which is adapted to be inserted in the tie.

Intermediate each of the tongues 4 and the ends of the tie on one side thereof I preferably provide the recesses 6, which are cut from the tie as clearly shown in Fig. 1 and provided with the beveled walls 7. The metal which remains after the recess has been cut is preferably bent toward the center of the recess, as clearly illustrated at 8, from whence it is bent upwardly and rear-

wardly, as shown at 9, to engage the web of the rail. This portion 9 is extended as illustrated at 10 and is adapted to overlie a portion of the tie immediately adjacent the recess. On the side of the tie opposite the recesses previously mentioned I preferably provide the recesses 11, which are of greater width than the aforementioned recesses to permit the fish plate of rail joints to rest between the edges of the recesses and bear against the block 5 when the device is in use. Suitable spike receiving notches are formed in the walls immediately adjacent the recesses 6 and are adapted to receive the spikes 12 which firmly hold the rail in place.

It will be clearly seen from the foregoing that in use my improved tie is placed in position as illustrated in Fig. 1 for a straightaway track and when it is desired to lay a curve the tie is reversed as shown in Fig. 2 which will give the rails room between the extremities of the recesses to take the proper contour of the track. It will be also apparent that owing to the recesses 11 which are in the bottom of the tie, when in use as shown in Fig. 1 the bedding surface of the road will come in contact with the wood block and more firmly bite thereagainst and thereby prevent any lateral slipping of the tie which would cause the track to become kinked and out of alignment. When the tie is in use as illustrated in Fig. 2 it is particularly adapted as above mentioned for curves, but may also be used for rail joints and owing to the fact that the tongues formed by the portions 8 and 9 are downwardly extended it will be obvious that they will engage the bedding surface of the road and lateral displacement of the tie with relation to the rails will be entirely eliminated, thus assuring that the track will be absolutely free of any kinks and the like, and preventing accidents caused by such inaccuracies.

While in the foregoing I have shown and described the preferred embodiment of my invention I wish it to be understood that I may make such changes in the combination and arrangement of parts as may fall within the scope of the claims herewith appended.

What is claimed is:—

1. In a device of the character described, a rectangular casing having recesses near each end on opposite sides, the metal cut from one pair of said recesses being bent up-

wardly and rearwardly to form a rail clamp and brace, the other of said recesses being of greater width than the first mentioned recess, tongues formed intermediate the recesses and extending inwardly, and blocks adapted to be driven into the end of the tie and against the said tongues, said blocks being adapted to act as supports for the rail.

2. In a device of the character described
10 a rectangular casing, said casing having recesses near each end on opposite sides thereof, one set of recesses being of greater width than the other set of recesses, each of the narrower recesses having spike receiving
15 apertures communicating therewith and formed in its inner wall, tongties formed from the metal left after cutting the recesses, said tongues being integral with the outer wall of said recesses and bent up-

wardly and inwardly to form rail clamping members, said tongues being bent back upon themselves and engaging the surface of the tie immediately adjacent the point where they join the tie, and tongues intermediate each set of recesses, said tongues being bent 25 inwardly and formed of the metal between cuts in the tie intermediate the recesses, and blocks adapted to be inserted in the ends of the tie and abut the tongues, said blocks being adapted to form seats for the rails when 30 the device is in use.

In testimony whereof I affix my signature in presence of two witnesses.

PETER J. PECK.
